Attorney.

UNITED STATES PATENT OFFICE.

MARCUS B. BEHRMAN, OF NEW YORK, N. Y.

SEAL-TAG.

1,254,021.

Specification of Letters Patent. Patented Jan. 22, 1918.

Application filed October 21, 1916. Serial No. 126,868.

To all whom it may concern:

Be it known that I, MARCUS B. BEHRMAN, a citizen of the United States, residing at the city, county, and State of New York, have 5 invented certain new and useful Improvements in Seal-Tags, of which the following is a specification.

This invention relates to a combination seal and tag which is to be attached to an 10 article of merchandise and which cannot be removed without mutilation.

The device is especially designed to be attached to garments or other articles of wearing apparel to prevent unauthorized use 15 thereof.

The invention consists of a seal comprising a receptacle containing legend-bearing cards which are displayed to view through 20 openings at the front and back of the receptacle, a pin adapted to be inserted and permanently held in the receptacle, and a string connecting said parts, which string must be cut to remove the seal from the article to which it is attached.

25 The invention consists further of certain novel details of construction which will be fully described hereinafter and pointed out in the claims.

In the accompanying drawings illustrating 30 my invention, Figure 1 is a fragment of a garment with my improved seal tag shown as attached through the button holes, Fig. 2 shows the opposite face of the tag, Fig. 3 and Fig. 4 are views of the two detached 35 halves of the receptacle, showing the interior of each, Fig. 5 is an enlarged cross section through the receptacle on the line 5-5 of Fig. 4, Fig. 6 is a view of the insertion pin and, Fig. 7 shows a modification of the pin.

40 Similar reference characters indicate similar parts throughout the several views.

Referring to the drawings, 1 and 2 indicate the two halves or parts of the receptacle frame, one of which fits into the other, as 45 seen in Fig. 5, and are inseparably fastened together in any suitable manner. The frame pieces have right-angled flanges which overlap the marginal portions of the tag-cards 3 and 4 and hold them in place so 50 that the legends placed thereon are visible through the open spaces at the front and back of the receptacle.

At the top of the receptacle is an aperture 6, through which the two ends of the string 55 7 are passed and then knotted as at 8, or otherwise fastened within the receptacle to

prevent their being withdrawn. An aperture 9 is provided at the bottom for entrance of the insertion pin 10, which pin has an eye 11 in its middle through which the string 60 connecting the two parts of the seal is threaded.

Within the receptacle and disposed between the cards 3 and 4 is a filler 12, preferably made of card board, which is cut of 65 such size and shape as to fill the hollow interior of the receptacle and to hold the tag-cards firmly in contact with the flanges of the frame. Portions of the filler are cut away and removed at the top and bottom, as 70 shown in Fig. 4, to form cavities 13 and 14 to accommodate the knot 8 and the pin 10 respectively.

In fastening the two parts of the seal together, the pin 10 is inserted into the cavity 75 14 at the bottom of the receptacle through the aperture 9, the diameter of which is just large enough to permit of passage of the pin. When the pin is inserted in the receptacle, it will drop down and lie across the bottom 80 of the frame, as shown in Fig. 3, so as to close the aperture 9 and prevent withdrawal of the string which latter is permanently held in engagement with the pin by being threaded through the eye thereof. 85

In Fig. 7 I have shown a modified form of pin provided with spring barbs 15 which bend back as the pin is passed through the aperture 9 and then expand so as to permanently hold the pin in the receptacle. 90

In the foregoing description it will be apparent that when the seal is attached to an article it cannot be removed without mutilation or cutting the string.

Various changes in the form and construction of the device hereinabove described may be made without departing from the scope of this invention.

What I claim is:

1. In a tag holder for garments and the like, a hollow member having openings at two spaced points and being otherwise closed to prevent access to its interior, a flexible tie, means to secure one end of the tie in one of said openings, and a pin connected to the 105 opposite end of the tie and being of a diameter so as to be insertible in the other opening, and of a length to extend across said opening and engaging the wall in which said opening is formed and to be entirely housed 110 within the member interior to prevent withdrawal of the pin except by cutting the tie.

2. In a tag holder for garments and the like, a hollow member, a flexible tie, means to secure one end of the tie on the interior of said member, said member having an opening, and a pin connected to the other end of the tie and being of a diameter so as to be insertible in the opening and of a length to extend across said opening and be housed entirely within the member interior to prevent withdrawal of the pin and consequent removal of the tie except by cutting of the tie or mutilation of the member.
3. In a tag holder for garments and the like, a hollow receptacle having front and rear openings, display cards in the receptacle for display through said openings, a

filler in the receptacle interposed between said cards and having cut-away parts and said receptacle having openings in register with said cut-away parts of the filler, a flexible tie having one end extending through one of said openings and secured to the receptacle in the adjacent cut-away part of the filler, and a pin on the other end of the tie of a diameter so as to be insertible in the other of said openings and of a length so as to extend across said opening and be entirely housed within the member interior to prevent removal of the pin except by mutilation of the member or removal of the tie except by cutting the latter.

MARCUS B. BEHRMAN.
